D. L. SPRAKER

GRINDING TOOL

Filed May 21, 1926

UNITED STATES PATENT OFFICE.

DAVID L. SPRAKER, OF INDIANAPOLIS, INDIANA, ASSIGNOR TO SPRAKER MANUFACTURING COMPANY, OF INDIANAPOLIS, INDIANA, A CORPORATION.

GRINDING TOOL.

Application filed May 21, 1926. Serial No. 110,681.

This invention relates to a grinding tool and particularly that type of tool adapted for grinding valves in internal combustion engines.

5 The principal feature of the invention resides in the mechanism for rotating first in one direction and then in another a grinding tool through continuous rotation of another member.

10 The full nature of the invention will be understood from the accompanying drawings and the following description and claims:

15 In the drawings Fig. 1 is a central vertical section through the tool showing the shaft and handle in elevation. Fig. 2 is a front elevation thereof with the closure cap removed. Fig. 3 is a sectional view taken on line 3—3 of Fig. 2 and in the direction 20 of the arrows.

In the drawings there is shown a grinding tool comprising a shaft 10 having the usual grinding head 11 keyed to the free end thereof, said shaft being rotatably 25 mounted in a housing 12 through the medium of a bearing 13. Said housing 12 has a closure cap 14. Mounted on the housing there is an upwardly extending handle 15 provided with a metal shell 16 positioned 30 centrally in the lower end thereof, which shell provides the upper bearing for the shaft and is rigidly secured to the upper portion of the casing. A ball bearing 17 is mounted intermediate the upper part of 35 the shaft 10 and the top of the metal shell 16 so as to provide an end thrust bearing.

The pins 18 and 19 are secured to the shaft within the shell, the pin 18 being positioned adjacent the low portion of the 40 shell and the pin 19 being positioned adjacent the upper portion of the shell. The pins are positioned substantially equi-distant from the center of the shell but are offset angularly with respect to each other, 45 that is, lie in different radial planes. The shaft 10 is rotated through the medium of the respective pins 18 and 19 as will be hereinafter described.

Extending rearwardly from the center of 50 the housing 12 there is a bearing shell 21 in which is mounted a rotating shaft 22 operated through a lever 23 having a handle 24. Interiorly of the shell there is a star-wheel 25 which is mounted for rotation with

55 shaft 22. The star-wheel is provided with three radially extending cam fingers 26 which are offset from the plane of the wheel toward the pins and shaft 10. The radial fingers are of such length and so arranged as to mesh alternately with the pins 18 and 19.

The shaft 10 carries the pin 28 which secures said shaft in predetermined position within the housing through the assistance of another pin 29 thereby positioning pins 18 65 and 19 substantially equi-distant from the center of the star-wheel or shaft 22. Pin 29 is utilized for an additional purpose, to-wit, it alternately engages the stop faces 30 of an arcuate stop 31 positioned adjacent 70 the pin 29, and herein shown formed integral with the sleeve bearing 13.

In operation, the tool is held in position under pressure through the medium of handle 15, while the handle 24 is rotatable 75 constantly in a given direction. Rotation of the handle 24 causes a like rotation of the star-wheel 25. When one of the fingers or cams 26 of the star-wheel is in engagement with one of the pins 18 or 19 the other pin 80 will be out of engagement therewith. Likewise, as will be clearly observed, the star-wheel being rotated in its given direction, the pins 18 and 19 will be alternately rotated in opposite directions by reason of the 85 opposing direction of movement of the fingers 26 when in engagement therewith. The alternate engagement of the pins 18 and 19 will accordingly cause the grinding tool to rotate alternately, first in one direction and 90 then in the other. By reason of the wide central angle between the fingers 26, engagement of a finger or cam 26 with pin 19 will cease and the finger be disengaged before another finger engages pin 18, thus preventing interlocking of the tool by reason of the simultaneous engagement of the two pins.

The invention claimed is:

1. A grinding tool including a rotatable 100 shaft, a pair of pins on said shaft positioned in different radial planes and in different parallel planes transverse to the shaft, a triangular star-wheel having a plurality of radial extending fingers spaced apart, said 105 fingers being adapted to engage first with one pin and then with the other for rotating said tool in opposite directions, said fingers

being equi-distant from the axis of the star-wheel and the latter being between said parallel planes.

2. A grinding tool including a rotatable shaft, but a pair of pins on said shaft, means for engaging first one pin and then the other for moving the same in opposite directions,

and means for limiting the oscillatory movement of the pin supporting shaft for insuring engageable positioning of the pins.

10

In witness whereof, I have hereunto affixed my signature.

DAVID L. SPRAKER.
